UNITED STATES PATENT OFFICE.

ALBERT SCHOENHUT, OF PHILADELPHIA, PENNSYLVANIA.

DESIGN FOR CHILD'S SLED.

Specification forming part of Design No. 7,921, dated December 8, 1874; application filed November 3, 1874.
[Term of Patent 7 years.]

To all whom it may concern:

Be it known that I, ALBERT SCHOENHUT, of Philadelphia, Pennsylvania, have invented a Design for a Child's Sled, of which the following is a specification:

The figure in the accompanying drawing represents my design for the side of a child's sled, which is made in the form of a swan without legs, the body of the swan terminating below in the runner a.

I claim—

The design for the side of a sled, representing the body, neck, and head of a swan, combined with a runner, a, as set forth.

In testimony whereof I have signed my name to this specification in the presence of two subscribing witnesses.

ALBERT SCHOENHUT.
